United States Patent Office

Des. 221,526
Patented Aug. 24, 1971

221,526

BUILDING

Walter Fisher, Brookline, Mass., assignor to Fox Ledge Corp.

Filed Apr. 21, 1970, Ser. No. 22,543

Term of patent 14 years

Int. Cl. D25—03

U.S. Cl. D13—1

Des. 221,526

PAGE 2

FIG. 2

FIG. 3

FIG. 4

FIG. 1 is a perspective view of a building showing my new design, two sides of the building being visible;

FIG. 2 is an elevational view showing a third side of the building, the projecting wall, shown in FIG. 1, which would be visible to the right of the figure having been deleted for convenience of illustration;

FIG. 3 is an elevational view showing a fourth side of the building, the projecting wall, shown in FIG. 1, which would be visible to the right of the figure having been deleted for convenience of illustration; and

FIG. 4 is a top view.

I claim:

The ornamental design for a building, substantially as shown.
